DRAWER PULL OR THE LIKE

John J. Lubberts and Lambert J. Mulder, Grand Rapids, Mich., assignors to Tomlinson of High Point, High Point, N. C., a corporation of North Carolina

Application March 8, 1957, Serial No. 45,157

Term of patent 14 years

(Cl. D10—8)

FIG. 1

FIG. 2

Fig. 1 is a front elevational view of a drawer pull embodying our new design;

Fig. 2 is a top plan view thereof;

Fig. 3 is a rear view thereof; and

Fig. 4 is an end view thereof.

We claim:

The ornamental design for a drawer pull or the like, substantially as shown.
